G. A. BOOMER.

BOWL HANGER FOR SEMI-INDIRECT LIGHTING FIXTURES.

APPLICATION FILED MAR. 29, 1917.

1,260,863.

Patented Mar. 26, 1918.

UNITED STATES PATENT OFFICE.

GEORGE A. BOOMER, OF WATERBURY, CONNECTICUT, ASSIGNOR TO THE PLUME & ATWOOD MFG. CO., OF WATERBURY, CONNECTICUT, A CORPORATION.

BOWL-HANGER FOR SEMI-INDIRECT-LIGHTING FIXTURES.

1,260,863.

Specification of Letters Patent. Patented Mar. 26, 1918.

Application filed March 29, 1917. Serial No. 158,212.

To all whom it may concern:

Be it known that I, GEORGE A. BOOMER, a citizen of the United States, residing at Waterbury, in the county of New Haven 5 and State of Connecticut, have invented a new and useful Improvement in Bowl-Hangers for Semi-Indirect-Lighting Fixtures; and I do hereby declare the following, when taken in connection with the accompanying drawings and the characters of 10 reference marked thereon, to be a full, clear, and exact description of the same, and which said drawings constitute part of this application, and represent, in—

15 Figure 1 a view in side elevation of one form which my improved bowl-hanger for semi-indirect lighting fixtures, may assume.

Fig. 2 an underside view thereof.

Fig. 3 a corresponding view of the shell 20 with its complement of fixed radially arranged rigid hanger-arms removed.

Fig. 4 an enlarged detail sectional view on the line 4—4 of Fig. 2.

Fig. 5 a view partly in side elevation and 25 partly in vertical section, of one of the several modified forms which my invention may assume.

My invention relates to an improved bowl-hanger for semi-indirect lighting fixtures, 30 the object being to produce, at a low cost for manufacture, a simple, convenient and attractive bowl-hanger of the character described.

With these ends in view, my invention 35 consists in a bowl-hanger characterized by a plurality of radially arranged rigid hanger-arms having their upper ends fixed to a hanger-head, and their lower ends formed with upturned, downwardly opening goose-necks for the reception of the rim of the 40 bowl, the outer ends of the said goose-necks being furnished with suspension means.

My invention further consists in a bowl-hanger for semi-indirect lighting fixtures, 45 having certain details of construction as will be hereinafter described and pointed out in the claims.

In carrying out my invention as shown in Figs. 1 to 4 inclusive, I employ three fixed, 50 radially arranged, rigid hanger-arms 5 made of heavy wire and having their diverging lower ends bent to form upstanding, downwardly opening, goose-necks 6 for the reception of the edge of the bowl which is 55 not shown, the outer ends of the goose-necks

being bent downwardly and formed with threaded openings for the reception of suspension screws 7 entering the spaces inclosed by the said goose-necks, and providing points from which the bowl is suspended. 60 The outwardly turned rim of the bowl rests upon the upper faces of the projecting inner ends of these screws. The upper ends of the said hanger-arms 5 are flattened and bent in the vertical plane to form fastening-fingers 8 which are passed upward through slots 9 formed near the outer edge of an annular horizontal flange 10 turned inward at a right angle from a collar 11 at the lower end of a hanger-head in the form of a ceiling-shell 12 the flange 13 of which is perforated as at 14 for the reception of screws by means of which the shell is fastened to the ceiling. The said fingers 8 are formed with threaded openings for the reception of 70 screws 15 passing through the collar 11, whereby the arms 5 are rigidly secured to the hanger-head in fixed relation to each other. The concentric opening 16 of the flange 10 receives a suitable lamp-socket, 75 80 which is not shown.

In the modified construction shown by Fig. 5, the fixed, radially arranged, rigid hanger-arms 5 having goose-necks 6 and suspension screws 7 are fastened by rivets 17 85 within the lower edge of a ring-like hanger-head 18 formed at its upper end with screw threads 19 for the reception of a threaded collar 20 which is formed at its upper end with an inwardly turned suspension-flange 90 21 resting upon an outwardly turned lip 22 at the lower end of a ceiling-shell 23. This construction provides for the rotation of the hanger-head 18 with respect to the shell 13 which is in some cases desirable. 95

I claim:—

1. In a bowl-hanger for semi-indirect lighting fixtures, the combination with a ceiling-shell, of a plurality of radially arranged rigid hanger-arms having their upper ends connected to the said shell in fixed relation thereto and their lower ends formed with upturned downwardly opening goose-necks for the reception of the rim of a bowl, and set-screws carried by the said goose-necks for securing the rim of the bowl therein. 100

2. In a bowl-hanger for semi-indirect lighting fixtures, the combination with a ceiling-shell adapted to be directly applied 105 110

2
to a ceiling, of a plurality of radially arranged rigid hanger-arms having their upper ends fastened in fixed relation to the lower end of the said shell and having their 5 lower ends formed with upturned, downwardly opening goose-necks for the reception of the rim of a bowl, and set-screws carried by the said goose-necks for securing the rim of the bowl therein.

10 3. As a new article of manufacture, a rigid hanger-arm for use in the manufacture of semi-indirect lighting fixtures, the said arm being adapted at its upper end to be rigidly fastened to a member of the fixture 15 and having its lower end formed with an upturned, downwardly opening goose-neck for the reception of a rim of a bowl, and the outer end of the said goose-neck being furnished with a set-screw for securing the rim 20 of the bowl in the goose-neck.

4. A removable attachment for a socket-cover, comprising an arm having a flat end bent upwardly at an inclination and provided with an opening for the passage of a set-screw of said cover by means of which the arm is connected to said cover, the other end of the arm being bent into substantially an inverted U-shape to receive the rim of a bowl, and a set-screw for securing the bowl therein.

25 5. In a bowl-hanger for lighting fixtures, an arm having a flat end extending upwardly at an inclination to the body of the arm to form a fastening finger and adapted to receive a fastening device, the other end of the arm being bent into substantially an inverted U shape to receive the rim of a bowl, and a screw in said U-shaped end to secure the bowl therein.
